(57) **CLAIM**

We claim the ornamental design for a monitor, as shown and described.

DESCRIPTION

FIG. 1 is a front perspective view of a monitor showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 2;

FIG. 11 is an enlarged view of the encircled portion 11 in FIG. 2;

FIG. 12 is an enlarged view of the encircled portion 12 in FIG. 3;

FIG. 13 is an enlarged view of the encircled portion 13 in FIG. 4;

FIG. 14 is an enlarged view of the encircled portion 14 in FIG. 5;

FIG. 15 is an enlarged view of the encircled portion 15 in FIG. 6;

FIG. 16 is an enlarged view of the encircled portion 16 in FIG. 8; and,

FIG. 17 is an enlarged view of the encircled portion 17 in FIG. 8.

(Continued)

The evenly-dashed broken lines in the figures depict portions of the monitor which form no part of the claimed design.

The dot-dash broken lines represent the boundary of the enlarged portions and form no part of the claimed design.
